UNITED STATES PATENT OFFICE

ANDRÉ LÉON VICTOR CLÉMENT DEBRIE, OF PARIS, FRANCE

CINEMATOGRAPHIC PRINTING MACHINE

Application filed January 23, 1932, Serial No. 588,889, and in France November 25, 1931.

My invention has for its object improvements in cinematographic printing machines working through contact whereby it is possible to obtain directly the printing of the titles, texts, explanations, etc. . . . on positive films during the picture printing without resorting to the costly method which consists in previously printing these titles on the negative film carrying the pictures.

10 The device which is the object of my invention allows, through a suitable combination of the parts, the printing of the titles in any desired manner without stopping the unwinding of the picture-carrying film.

15 In particular it is possible to print the titles, texts or explanations alone without it being necessary to cut the negative for inserting transparent parts carrying no picture. It is also possible to obtain according to my invention a title or a text extending only over part of the height of the pictures, the scene being photographed on the remainder of the picture area apart from the title or text. It is also possible to print a title or text surrounded by a picture or superimposed on it.

20 Moreover the device according to my invention allows the automatic execution of the different luminous intensities required for scene printing without it being necessary to resort to the more or less intricate mechanisms used heretofore for varying the light intensity through the provision of circuits inserting different resistances in the circuit of the printing lamp.

25 My improved device comprises chiefly two projection lamps of which one has its beam passing through the negative on to the positive while the beam of the other falls directly on the positive which may be impressed through its support or back.

30 Between the first lamp and the negative is interposed an auxiliary strip which I will term hereinafter for simplicity's sake the "screen strip" although it does not always 35 perform exclusively the part of a screen; between the second lamp and the device is interposed a second auxiliary strip, which I will term hereinafter the "text strip".

35 The screen strip comprises opaque parts which may extend either over the whole height

of a picture or over only part thereof and which are adapted to intercept any light which might fall on the negative, these opaque parts being separated by transparent parts.

40 These transparent parts may instead of being of a uniform white or the like colour, be more or less shaded and show a variable transparency. The shade may be moreover degraded and show a gradually varying transparency from one end to the other of the picture. Similarly the transparent parts extending over a part of the picture the remainder of which is screened may be more or less shaded. Lastly this screen strip may also carry texts.

45 As to the text strip, it carries titles or texts in black on a white background or in white on a black background, which extend either over the whole height of the picture or over part thereof only. The text strip 50 also comprises entirely opaque parts.

55 The text and screen strips move simultaneously through the action of any suitable means. As to the negative and positive strips, they move as usual in a continuous manner 60 in contact one with the other, the two gelatine coated surfaces facing one another.

65 Different combinations of which this arrangement allows the execution will be described hereinafter with reference to accompanying drawing.

70 Fig. 1 is a diagrammatic view of the whole arrangement.

75 Fig. 2 and Fig. 3 show respectively a form of execution of the text strip and of the screen strip.

80 Fig. 4 illustrates a practical form of execution of the invention.

I have shown in Fig. 1 the negative film 1 and the positive film 2 which advance 85 simultaneously through the printing machine in an uninterrupted manner with their gelatin-coated surfaces facing one another and in contact one with the other. A first lamp 3 sends its beam on to the negative film 90 and through the latter on the positive film. The screen strip 4 constituted in the manner described moves parallel to the negative and positive films and is arranged across the path of the light rays issuing from the lamp 95 100

3, between the latter and the negative 1. On the other hand a second lamp sends its light beam on to the rear of the positive film 2. the text strip being interposed across the 5 path of the beam and moving parallel to the films 1 and 2 in synchronism with the screen-strip 4.

The arrangement being as described, different cases are to be considered.

10 1—the screen strip 4 shows in the part through which the rays from the source 3 pass a transparent part throughout the height of the picture, as shown at 7 in Fig. 3; at the same time the text strip 6 shows 15 in the part through which the rays from the source 5 pass an opaque part throughout the height of the picture as shown at 7 in Fig. 2.

This case corresponds to ordinary printing using the full intensity of the lamp 3, 20 the positive film being printed in the usual manner through the negative. This printing is performed during the passage of a certain number of negative pictures, say 200 while the strips 4 and 6 remain stationary.

25 2—the screen strip 4 shows a more or less shadowed part throughout the picture as shown at 8 in Fig. 3, while the text strip 6 which has moved together with the strip 4 shows throughout the picture area an opaque 30 part 8' (Fig. 2). The image of the negative is printed on the positive, but with an intensity which is reduced due to the shadowed part on part strip 4. This case is that of normal printing but with a reduced 35 illumination. This shadowed printing may last, for a given intensity of illumination, during the passage of a certain number of negative pictures, say 100, the strips 4 and 6 remaining of course stationary during this 40 time.

3—the screen strip 4 shows an opaque part throughout the picture area as shown at 9 (Fig. 3) while the corresponding part 9' of the strip 6 (Fig. 2) carries throughout the 45 height of the picture area a title or letter-press in black on white background or in white on black background. The picture on the negative cannot be printed on the positive because the rays from the lamp 3 are 50 arrested by the strip 4; on the contrary the text carried by the strip 6 is printed on the positive through the support thereof in white on black background or reversely according to the case. This printing continues while 55 say 50 unimpressed picture areas of the negative pass through the machine, the strips 4 and 6 remaining stationary during this time.

4—the screen strip 4 shows a transparent part 10 throughout the picture area and carries a text in black letters which prevent the passage of the light from the lamp 3, the corresponding part 10' of the text strip being completely opaque. Consequently the negative picture is printed on the positive except 65 in front of the letters formed on the strip

4 whereby I obtain finally on the positive white letters surrounded by the picture.

5—the screen strip 4 shows a part 11 transparent throughout the picture area while the corresponding part 11' of the text strip 6 is opaque throughout the picture area and carries white letters which allow the light to pass. The image of the negative is printed entirely on the positive while the letters of the text strip are printed in black over the picture.

6—the arrangement being the same as in the cases 4 and 5, the transparent parts of the screen band 4 are more or less shadowed whereby the printing is effected through the negative with a corresponding reduced intensity.

7—it is possible to retain the same conditions of printing as in above case 4, but with a degraded shadowed part for strip 4, the lesser shadow being provided round the letters. I obtain thus on the positive a picture which is blacker round the white letters which appear thus more sharply.

8—under the same conditions as in case 9, I may give the strip 4 a degraded shadow the maximum of which appears in the part corresponding to the letters of the strip 6. The positive picture is thus lighter round the black letters.

9—the screen strip 4 shows a transparent part over a more or less considerable height of the picture and is opaque over the remainder of this height (as shown at 12 in Fig. 3). It forms thus a mask; the strip 6 shows a part 12' forming a complementary mask for the parts which are not covered by the mask on strip 4 and carries in its remaining transparent part black letters.

The image of the negative corresponding to the transparent part of 12 is printed on the positive and the letters of 12' are printed in white on black on the remaining part of the positive.

10—the screen strip 4 appears as in case 110 9 above as concerns the part 13 used on it (Fig. 3), but the strip 6 is opaque and carries transparent letters in the part corresponding to the opaque part of the strip 4 as shown at 13' (Fig. 2) consequently the positive carries a picture corresponding to the transparent part of 13 and black letters on a white background on the remaining part of its picture area.

11—Lastly under the same conditions as 120 for cases 9 and 10, the transparent part of the strip 4 is darkened to the desired extent.

Obviously the different parts 7, 8, 9, 10, 11, 12, 13 of the strip 4 and the corresponding parts of the strip 6 may succeed one another 125 in any desired order, several parts such as 8 having different degrees of transparency being arranged in sequence.

In those cases where the negative already 130 carries a text, the combinations 9, 10, 11 above

disclosed allow the substitution therefor of another text, which may be written e. g. in another language, without touching the original negative.

5 I have shown in Fig. 4 a form of execution of a printing machine provided with the improvements which are the object of the present invention. The casing 14 of the machine is provided on one side with a printing channel through which the negative film 1 and the positive film 2 are adapted to move the emulsions on these films facing one another. Both films are uninterruptedly driven by a suitable control mechanism not shown.

10 15 To a control shaft 16 the control means of which are not shown, are keyed two toothed drums 17, 18 adapted to drive respectively at each change in the text to be printed or in the intensity of the picture printing the 20 screen strip 4 and the text strip 6.

Behind the screen strip 4 is disposed a lantern 19 enclosing the lamp 3 the light of which passes through the condenser 20, the strip 4 and inside the case 14 the objective 25 21 after which it falls on a prism or mirror 22 which reflects it laterally on to the negative 1 and through the latter, on to the positive 2.

On the other hand, behind the text strip 30 35 40 6 is disposed a second lamp 5 enclosed in a second lantern 23 and the light of which passes through the condenser 24, the strip 6 and the objective 25 after which it falls on a prism or mirror 26 which reflects it on to the rear side of the positive film 2 which is thus impressed through its support.

The shutter 27 is adapted to intercept the light passing out of the lamps during the simultaneous advance movements of the films 40 1 and 2.

What I claim is:

1. A device for the simultaneous printing of titles and pictures on a positive comprising a negative film, a positive film, a printing gate, means for making both said films advance simultaneously throughout operation through said gate, a title band including opaque portions on the side of the positive film opposed to the negative, a screen band including opaque portions on the other side of the films, means for advancing the corresponding portions of both bands in front of the gate as required by the progress of operation and means for simultaneously illuminating the positive film through the title band on one hand and through the screen band and negative film on the other.

2. A device for the simultaneous printing of titles and pictures on a positive comprising a negative film, a positive film, a printing gate, means for making both said films advance simultaneously throughout operation through said gate, a title band including opaque portions on the side of the positive film opposed to the negative, a screen

band including opaque portions corresponding to a series of picture areas through part of the height thereof on the other side of the film, means for advancing the corresponding portions of both bands in front of the gate as required by the progress of operation and means for simultaneously illuminating the positive film through the title band on one hand and through the screen band and negative film on the other.

3. A device for the simultaneous printing of titles and pictures on a positive comprising a negative film, a positive film, a printing gate, means for making both said films advance simultaneously throughout operation through said gate, a title band including opaque portions on the side of the positive film opposed to the negative, a screen band including opaque portions corresponding to a series of picture areas through the entire height thereof on the other side of the films, means for advancing the corresponding portions of both bands in front of the gate as required by the progress of operation and means for simultaneously illuminating the positive film through the title band on one hand and through the screen band and negative film on the other.

4. A device for the simultaneous printing of titles and pictures on a positive comprising a negative film, a positive film, a printing gate, means for making both said films advance simultaneously throughout operation through said gate, a title band including opaque portions on the side of the positive film opposed to the negative, a screen band including opaque portions and portions of varying opacity on the other side of the film, means for advancing the corresponding portions of both bands in front of the gate as required by the progress of operation and means for simultaneously illuminating the positive film through the title band on one hand and through the screen band and negative film on the other.

5. A device for the simultaneous printing of titles and pictures on a positive comprising a negative film, a positive film, a printing gate, means for making both said films advance simultaneously throughout operation through said gate, a title band including opaque portions on the side of the positive film opposed to the negative, a screen band including opaque portions and portions of varying opacity round the portion corresponding to the title on the corresponding portion of the title band on the other side of the films, means for advancing the corresponding portions of both bands in front of the gate as required by the progress of operation and means for simultaneously illuminating the positive film through the title band on one hand and through the screen band and negative film on the other.

6. A device for the simultaneous printing

of titles and pictures comprising a negative film, a positive film, a printing gate, means for making both said films advance simultaneously throughout operation through said gate, a title band including opaque portions, a screen band including opaque portions, means for advancing the corresponding portions of both bands in front of the gate as required by the progress of operation and illuminating means for impressing the positive with the pictures of the negative through the screen band and with the titles on the title band.

In testimony whereof I have affixed my
15 signature.
